ROBERT N. SCHALKENBACH, DECEASED, LATE OF BALTIMORE, MARYLAND, BY
HULDA W. SCHALKENBACH ADMINISTRATRIX, OF BALTIMORE, MARY-
LAND.

GLAZED STRUCTURE.

Substitute for abandoned application Serial No. 760,880, filed April 14, 1913. This application filed No-
vember 14, 1921. Serial No. 515,102.

To all whom it may concern:

Be it known that ROBERT N. SCHALKENBACH, deceased, who was a citizen of the United States, and who resided at Baltimore, in the county of Baltimore, State of Maryland, invented certain new and useful Improvements in Glazed Structures, of which the following is a full, clear, and exact description.

10 My invention relates to improvements in structures embodying metallic members supporting panes of glass and which are of a permanent nature and are "puttyless," that is to say, no use is made therein of cement, putty or similar binding material.

Among the objects of my invention is the provision of a simplified form of structure, which is easily made and assembled; in which ordinary commercial shapes of materials may be used, thus avoiding the necessity for the use of expensive, specially constructed shapes; in which the cushioning means for the glass is completely protected from dirt and moisture; in which thorough provision for excluding moisture from the interior of the structure is made; in which the application of pressure to the edges of the glass and the consequent liability of breakage is avoided. Other objects are the provision of novel means for retaining and holding the members for supporting the glass in place, the provision of novel means for closing the spaces beneath the glass and between the supporting members, the provision of novel means for causing the discharge of water of condensation and all other water that may find its way into the interior of the structure, and generally in the simplification and improvement of structures of the character referred to.

Other objects of my invention will appear hereinafter and be pointed out in the claims and with the foregoing objects in view, my invention consists in the parts, improvements and combinations herein set forth and claimed; and while I have illustrated a particular construction in which my invention may be embodied, it is to be understood that the same is for the purpose of illustration only and that my invention is not confined thereto but is as broad as my claims, and that various changes may be made in the construction illustrated with-

out departing from my invention or sacrificing any of the advantages thereof.

In the drawings forming a part of this specification, and wherein the same reference numerals are made use of to designate the same parts throughout,

Figure 1 is a view in perspective and partly in transverse cross-section of a longitudinal joint structure made in accordance with my invention;

Figure 2 is a longitudinal view partly in section of the joint structure shown in Figure 1, and showing the lower end or edge of a skylight or roof structure;

Figure 3 is a detail perspective of an expansion clip made use of in connection with my invention;

Figure 4 is an end view of the parts shown in Figure 2, looking in the direction of the arrow on Figure 2;

Figure 5 is a plan view of an expansion clip;

Figure 6 is a sectional detail view;

Figure 7 is a detail cross-sectional view of the joint cap before the parts are assembled; and

Figure 8 is a similar view of the means for closing the openings between the glass and curb.

In the said drawings, the reference numeral 1 is applied to a supporting bar having the form of a T-beam. These supporting bars 1 run parallel to one another from the highest to the lowest point of a skylight or other glazed structure and one is provided between each width of glass allowing ample clearance at the edges of each width of glass to provide for lateral expansion and contraction, the width of each sheet of glass being preferably not to exceed eighteen inches, although the precise width of glass for the distance between T-beams will vary with different structures, and with different thicknesses of glass.

The supporting bars 1 are securely fastened in place at their upper ends (not shown) and the expansion and contraction of the supporting bars is taken care of at the lower ends, as will be described hereinafter. The T-beams are placed in position with the flanges 2, 2 extending horizontally on each side and with the intermediate flange or web 3 extending vertically

upward between the side flanges 2, 2. The glass is shown at 4 and the edges of the panes of glass are supported upon the side flanges 2, 2 of the T-beams 1, and obtain 5 a broad flat bearing thereon.

Means is provided for securing a soft flexible cushioning support for the glass 4 upon the flanges 2, 2 and such means may take the form of comparatively broad flat 10 strips of suitable material 5 resting directly upon the flanges 2, 2 of the T-beams 1. The glass 4 is not placed directly upon this soft elastic cushioning means, as such an arrangement might result in water, condensed on 15 the undersurface of the glass, or getting through any cracks which might be formed in the glass coming into contact with and penetrating the porous cushioning means resulting in its becoming caked and hardened 20 and filled with dirt and likely to freeze and expand in freezing weather and cause breakage of the glass. In order to prevent such action, I provide metallic means for covering the cushioning means 5 which is preferably 25 formed of a strip of soft copper 6, placed between the cushioning means 5 and the glass 4, and this strip 6 of copper or similar material is extended inwardly under the glass beyond the cushioning means 5, and is 30 bent downward at 7, bent inwardly at 8 and upwardly at 9, to form a gutter 10, the upper edge 11 of the gutter 10 being spaced below and not in contact with the glass 4, and leaving a slight opening between the edge 11 and 35 the lower surface of the glass 4. All water of condensation and all water penetrating within the structure will be collected within this gutter 10 and carried off as explained hereinafter.

40 In order to still further protect the cushioning material 5 and to prevent access of dirt or water thereto, the cushion covering means 6 is extended upwardly at the edge adjacent to the web 3 of the T-beam 1, as 45 shown at 12 so that any water getting past the inner edge 13 of the glass 4, will not penetrate to the cushioning material 5, but will be carried along the strip 6 underneath the glass 4 and into the gutter 10. A clearance is provided beneath the inner edges of 50 the glass 4 and the web 3 of the T-beams 1, so that the glass is free to contract and expand toward and away from the web 3 of the T-beams 1, and the upwardly extending edge 12 of the strip 6 is also spaced slightly 55 away from the edge 13 of the glass for a like purpose. In order to prevent the edges of the glass 4 in adjacent sections slightly away from one another so as to prevent 60 looseness and vibration, I provide expansion clips 14 of substantially U-shape and fitting over the top of the web 3 of the T-beams 1 and having spring projecting portions 15, which bear against the upwardly extending 65 edges 12 of the strips 6 and which at the

same time will give sufficiently to accommodate any expansion and contraction of the glass which may take place. One of these clips 14 is preferably provided at each of the bolts 16 hereafter referred to and the clips 70 14 are provided with openings 17 through which the bolts 16 may pass. To still further protect the interior of the structure and cushioning means 5 from the ingress of water from above and in order to provide a 75 comparatively soft self-adjusting cushion for the spring cap or cover which completes the structure, I have provided an additional cushioning means 18 which is preferably formed from strips of soft lead. These 80 strips comprise the portions 19 lying flat on the upper surface of the glass, opposite to and above the cushioning means 5, and an upwardly extending portion 20, which forms a dam for excluding water and other material 85 from ingress to the interior of the structure, and a downwardly extending, reversely bent portion 21 extending over the top and down on the inside of the upwardly projecting portion 12 of the cushion protecting means 6, this construction serving to secure together the lead strips 18, and the cushion covering strips 6 which have the gutters 10 formed thereon, preventing strips 6 and 18 90 from coming loose and getting out of place. 95

The joint is completed by a spring cover or cap 22 which is preferably formed of copper and comprises a flat or approximately flat top portion 23, downwardly and outwardly extending flat portions 24, and 100 lower surfaces 25, 25 which extend inwardly and at an acute angle to the downwardly extending portion 24, 24 and rest flat on the flat portions 19 of the lead strips 18 which themselves rest directly upon the glass, and 105 have a bearing thereon.

Means is provided for securing the spring cap or cover 22 in place and preferably comprises the bolts 16 provided with heads 26 received in undercut openings 27 in the 110 web 3 of the T-beams 1, although, of course other means than that shown may be resorted to for this purpose. In order to provide against unequal expansion between the T-beams 1 and the caps 22 and to facilitate 115 the work of erection, the openings 28 provided in the cap 22 for the passage of bolts 16 are somewhat elongated and washers or cover plates 29 are provided having openings 30 of the correct size to accommodate 120 the passage of bolts 16, as is shown in Figure 6. After the cap has been put in place and the cover plates or washers 29 have been inserted over the bolts 16, the nuts 31 are screwed on the bolts 16 to hold all the 125 parts together with the requisite degree of tightness. The inwardly extending portions 25 of the caps 22 are initially bent downward somewhat from the horizontal as shown in Figure 7, so that when the parts 130

are secured together by screwing up the nuts 31, the portions 25, in addition to having a flat bearing throughout the width upon the strips 19, also serve to exert a 5 spring action, thus increasing the tightness of the joint and holding the lead strips 19 with a fair degree of firmness against the top of the glass 4 and in such manner as to conform to any irregularities which may be 10 found in the surface of the glass.

The T-beams 1 rest, at their lower ends, upon the expansion clips 32 which are secured to the supporting member, such as the curb 33, by any convenient means, as 15 for example, the wood screws 34 passing through openings 35 in lugs 36 extending outward from the expansion clips 32. These lugs may be dispensed with, if desired, and the openings 35 formed within the side lines 20 continued, of the expansion clips 32.

Means is provided for holding the supporting bars or T-beams 1 at their lower ends and at the same time permitting longitudinal expansion and contraction of the T- 25 beams 1, and such means preferably takes the form of lugs 37, 37 which project over the flanges 2, 2 of the T-beams 1 and have a slot or opening 38 formed therebetween to receive the web 3 of the T-beams 1. This 30 arrangement prevent all other movement of the T-beams 1, but leaves them free to contract or expand lengthwise of the T-beams being firmly secured at their upper ends as already described, an adequate and satisfactory fastening therefor is thus provided.

Suitable means is provided for closing the openings which would otherwise be left above the supporting curb 33 and below the lower surface of the glass 4 intermediate of 40 the T-beams 1, and means for holding such closing means in place may be provided by leaving vertical slots or openings 39 in the sides of the expansion clips 32 for the reception of the ends of the members provided 45 for closing the space between the glass and the curb or other member upon which the structure is supported. The members for closing this opening are shown in cross-section at 40 and comprise flat lower surfaces 41, upwardly extending portions 42, rearwardly bent portions 43 and reverse outwardly bent portions 44, and the closing members 40 are placed with their flat portions 41 bearing directly upon the supporting curb or other member 33, with the upright portions 42 closing the opening between the glass and the curb, and the backwardly and forwardly bent portions 43 and 44 immediately beneath the former in contact with the lower surface of the same. A recess 45 is provided in the upper surfaces of the clips 32 for receiving the reversely bent portions 43 and 44 of the closing members 40, which members 40 are preferably 55 formed of copper and the reversely bent

portions 43 and 44 are preferably formed initially with a slight opening between them, as shown in Figure 8, and when the glass is placed thereon, the members 43 and 44 are pressed downwardly by the glass and are received within the recess 45. By forming and assembling these parts in the manner described, a broad flat bearing is provided for the glass on the upper reversely bent portion 44 of the closing member 40 and at

70 the same time the member 40 is brought into a spring contact with the glass 4 throughout its entire width notwithstanding any irregularities which may be present in the sheet of glass. The flat lower portion 80 41 of the closing member 40 rests directly upon the curb 33 or upon the apron formation 48, which is preferably placed upon the curb 33 when a wooden curb is used, and extends inward thereon to form a dis-

charge gutter of which the outer wall is formed by the upwardly extending portion 85 42 of the closing member 40. Openings 46 which may be of any convenient shape, and are preferably half round as shown in Figure 90 4, are provided in the wall 42 of the member 40 for permitting discharge of any water which may be discharged therethrough from the gutters 10. The gutters 10 extend part way over the lower portion 95 41 of the closing member 40 so that all water that gets into the gutters 10 will be discharged into the said closing member and thence be permitted to escape through the openings 46. The openings 46 are prefer-

ably not placed opposite the ends of the gutters 10, and are preferably arranged at a slight distance away from and at one side of the ends of the gutters 10 so that any dirt or other material which may be admitted through the openings 46 will not have a tendency to clog the gutters 10. The clips 100 32 are formed with a step 51 and with a lower surface 52 on which the ends of the T-beams rest and are confined by the lugs 105 37, and an upper surface 53 raised the height of the step 51 from the portion 52, the distance between the portions 52 and 53 being slightly less than the combined thickness of the flanges 2, cushioning covering means 6, 110 and cushioning means 5 when the latter is compressed, so that the glass 4 extending above the ends of the flanges 2 is given a slight clearance above the upper portion 53 of the clips 32. The clips 32 terminate at 115 their lower ends in upward extensions 47 having the same general outlines as the caps 22, as shown in Figure 4, thus making a neat finish and closing the ends of the caps, though a slight clearance may be left 120 to provide against expansion. A rib 50 may be formed centrally on the end of each upward extension 47 when the expansion clips are formed by casting, thus imparting additional strength thereto and adding to the

125 130

pleasing appearance of the completed structure. The cushioning material 5 is terminated at or slightly back of the lower ends of the T-beams 1 so that, while sufficient support for the glass will be afforded, there will be no opportunity for water or other material to come into contact with the cushioning means 5 at the lower end thereof, and, as already stated, the cushioning means 5 and its cover strip 6 are selected of proper thickness so that the glass 4 where it extends over the clips 32 beyond the ends of the T-beams 1 will not come into direct contact with the surface of the clip, but will be supported lightly above the surface thereof.

The functions of the various elements in my improved structure and the manner of its assembly and use appear sufficiently from the foregoing, so that further detailed description thereof is unnecessary.

Having now described my invention, I claim:

In a glazed structure, the combination of supporting T-beams placed with their side flanges down, cushioning means on said side flanges, members on said cushioning means having upward projections at the edges thereof adjacent to the web of the

T-beams and projecting beyond the upper surface of the glass and having their opposite edges formed into gutters, panes of glass supported on said members, metallic strips placed upon the upper surface of the panes of glass along their edges and having an upward projection at the inner edge thereof forming a dam to prevent the passage of water therebeyond and bent downwardly to interlock with the upward projection of the member extending from beneath the glass, bolts secured in said T-beams, a spring cap resting upon the members placed on the upper surface of the glass, and having openings for the passage of said bolts, and nuts on said bolts beyond the top of the cap for securing the parts together and in place, substantially as and for the purposes set forth.

In testimony whereof, I affix my signature, in the presence of two witnesses.

HULDA W. SCHALKENBACH,
*Administratrix of Robert N. Schalkenbach,
deceased.*
